UNITED STATES PATENT OFFICE.

ALFRED B. FOWLER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

KNIFE-GRINDING MACHINE.

1,318,441.

Specification of Letters Patent.

Patented Oct. 14, 1919.

Application filed December 8, 1916. Serial No. 135,815.

To all whom it may concern:

Be it known that I, ALFRED B. FOWLER, a citizen of the United States, residing at Beverly, in the county of Essex and State of Massachusetts, have invented certain Improvements in Knife-Grinding Machines, of which the following description, in connection with the accompanying drawings, is a specification, like reference characters on the drawings indicating like parts in the several figures.

This invention relates to grinding machines and more particularly to machines for grinding the edges of knives having curved cutting edges with or without concaved faces, such, for example, as the knives used for breasting the heels of boots and shoes.

The front or breast of the heels of boots and shoes has either a concave or a straight edge, both styles being used, and the shank of the shoe at the junction of the heel breast is usually convex. Heel breasting knives form the breast of the heel with a concave or straight transverse surface and cut the material of the heel down to the line of the shank. The edges of such knives must be ground to conform to the contour of the shank and, when the heel breast is concaved, they must be correspondingly curved transversely.

When this double curvature of cutting edge is to be ground, the knife and grinding member must not only have relative traverse in an arc having a radius equal to that of the concave face of the knife but there must also be relative movement longitudinally of the knife to conform to the curvature of the cutting edge lengthwise of the knife, so as to grind the edge at a uniform bevel and keep said curvature constant. When the knife is flat for cutting a straight breast, on the other hand, there must be relative traverse of the knife and grinding wheel in a straight line with coincident relative movement longitudinally of the knife.

My invention provides a grinding mechanism constructed to permit relative traverse of a knife holder and grinding wheel and coincidently to effect relative longitudinal

movement and arranged to grind laterally curved and straight breasting knives with equal facility, and in addition provides certain novel mechanism for effecting these results including novel and advantageous 55 adjustment and guiding means.

One feature of the invention consists in the combination of a grinding member and knife holding means constructed and arranged for relative traverse, with traverse 60 guiding means constructed and arranged to effect relative traverse along a line automatically determined by the transverse contour of the knife. More specifically and as a related feature, the knife holding means 65 includes a knife holder mounted for movement toward and from the grinding member and guiding means constructed and arranged to cooperate with the knife during relative traverse to conform the line of traverse to the transverse contour of the knife. 70

Such mechanism is particularly advantageous in that the line of traverse automatically conforms to the transverse contour of the knife edge whether this contour be 75 straight or curved. The automatic accommodation dispenses with the necessity of successive adjustments for curve variance or for the change from transversely curved to transversely straight knives. A machine 80 having these characteristics also obviates the necessity of special equipment for transversely straight and curved knives.

A feature of the invention consists in the combination of a grinding member and 85 knife holding means constructed and arranged for relative traverse, with a guiding member determinately and fixedly positioned to engage the rear face of the knife during such relative traverse to maintain 90 successive grinder-contacting portions of the opposite knife face uniformly spaced from said guiding member. This arrangement tends to secure uniform bevel of the cutting edge of the knife and to correct any original 95 unevenness in the transverse line of the cutting edge by grinding the edge to a uniform bevel.

A further feature of the invention consists in the combination of a grinding mem- 100

ber and knife holding means constructed and arranged for relative traverse, with guiding means constructed and arranged to effect relative traverse in a line automatically determined by the transverse contour of the knife and coincidently to effect bodily longitudinal projecting movement of the knife in the path of and during such traversing movement. A grinding machine embodying these characteristics in combination not only automatically conforms the line of traverse to the transverse contour of the blade but coincidently insures an invariable position for that portion of the edge of the knife which is in engagement with the grinder to secure a determined curve and a uniform bevel along the shank-conforming edge of the knife by confining the line of grinding contact during such traverse to the line of such curved edge so as to present successive portions of the knife edge at a uniform angle to the periphery of the grinding wheel.

In one embodiment, and as shown, a pattern or templet having an edge complementary to the curve of the knife edge lengthwise of said edge coöperates with the knife holder to raise and lower the edge of the knife during traversing action. The templet is detachably mounted so that different templets may be used for different edge curvatures.

A feature of the invention consists in the combination of a grinding wheel, a frame positioned in coöperative relation to the grinding wheel, a carriage guided on said frame for sliding movement transversely of the periphery of the grinding wheel and a knife holder mounted on and moving with said carriage and independently movable substantially perpendicularly to the line of transverse movement and also movable toward and from the periphery of the grinding wheel. This construction permits of the knife curve conforming movements of the knife holder during traverse of the carriage.

A related feature consists in the combination with the grinding wheel, frame, sliding carriage and knife holder mounted on and movable with the carriage and independently movable toward and from the periphery of the grinding wheel, of guiding means determinately and fixedly positioned to engage and maintain successive portions of the edge of the traversing knife uniformly in contact with the periphery of the grinding wheel, with means operative to hold the knife against said guiding means during traversing movement of the carriage and knife. In the construction shown, a spring holds the back face of the knife against a frame-carried guiding member which maintains the back of the knife a uniform distance from the periphery of the grinder and insures uniformity of thickness of the ground

edge. In addition, the same structure is equally efficient in guiding transversely straight and curved knives since the spring will automatically move and maintain the knife relatively to the periphery of the grinding wheel and against the guiding member when the knife is transversely curved so as to conform the line of transverse movement of the knife to the transverse curvature of the knife. 75

These and other features of the invention, including certain novel adjustment means for the frame and certain novel constructions of the frame, carriage and knife holder with its knife clamping and holding means, 80 will be more fully apparent from the detailed specification which follows when read in connection with the accompanying drawings in which:—

Figure 1 is a view in side elevation of a 85 grinding mechanism constructed in accordance with the present invention;

Fig. 2 is a rear elevation of the mechanism shown in Fig. 1;

Fig. 3 is a top plan view of the mechanism; and

Fig. 4 is a vertical section taken on the line 4—4 of Fig. 1.

A suitable bench 2 or other base is utilized as a support for an upstanding frame 4 supporting a grinding wheel 6 having a rounded relatively narrow periphery and driven by any suitable means, such as the pulley and belt, shown. 90

Secured to the bench or base 2 is a bracket 8 having a depending plate 10 terminating in an elongated portion provided with a longitudinal slot therein and with raised bearing faces around the edges of the slot. A frame block 12 extends substantially parallel with the slotted plate 10 and is formed with an offset portion 14 (Figs. 3 and 4) extending through the slot of the plate and having at one side bearing faces resting against the bearing edges of the slotted plate. On the opposite face of the bracket plate a separate bearing plate 16 is secured at one end to the offset 14 by means of a screw bolt 18 and bears against the bearing edges extending about the slot at that side 110 of the plate. The bracket plate 10 at its forward end is formed with a lateral offset 20 (Fig. 3) terminating in a smooth-bored bearing sleeve 22 through which extends an adjusting spindle 24, the outer end of which 115 is positioned at the front of the bench or support and is provided with a hand wheel 26 for manipulation by the workman. The other end of the plate 16 is secured to the offset 14 and is held against the bearing 120 edges of the bracket plate by means of an internally threaded sleeve 28 having a threaded stem 30 entering through the plate 16 into the offset 14 of the frame block 12. This sleeve 28 is locked to the frame block 130

by a check nut 32 and is carried by the threaded inner end of the adjusting spindle 24. This spindle is held against longitudinal movement in the bearing sleeve 22 by any suitable means such as collars 25 fixed to the spindle at the ends of the bearing sleeve by set screws 27 (see Fig. 3). Obviously, rotation of the adjusting screw 24 will move the sleeve 28 longitudinally of the bracket plate 10 and with it, will slide the attached frame block 12 longitudinally of said bracket plate to adjust the grinder frame supported by said block toward or from the grinding wheel 6. This adjustment means is utilized to move the knife toward the grinder for initial adjustment, additional grinding pressure or for adjustment in compensation for wear on the grinder. It may be used also to move the knife holder away from the grinder for the removal or insertion of a knife.

The forward end of the frame block 12 is bifurcated, as seen in dotted lines at 34, Fig. 3 and to receive a lug 36 (Figs. 1 and 3) extending rearwardly from a threaded sleeve 38 and pivotally connected to the end of the frame bar by a pin 40. The angular relation of the sleeve 38 to the frame bar 12 may be varied, in turn to vary the inclination of knife supporting parts carried by the sleeve 38 in any suitable manner. Preferably, and as shown, the sleeve 38 is provided with an offset 42, and the frame bar 12 at its end is provided with complementary lateral offsets 44 having aligned threaded bores therein, through which set screws 46, 48 extend to engage the upper and lower faces of the offset 42 and support and maintain the sleeve in angularly adjusted position relatively to the frame bar 12.

A threaded standard 50 extends vertically through the sleeve 38 and ringed threaded sleeves 52 on the standard at the upper and lower ends of the sleeve 38 act as check nuts to lock the standard 50 in vertically adjusted position.

The upper end of the spindle is threaded into the lower bar of a rectilinear frame 54 and is locked in position by means of a check nut 56. A rod 58 extends transversely of the frame adjacent to its lower end and is provided with a key 60 fitting in a keyway formed in a sliding carriage in the form of a sleeve 62 guided by the rod 58 and its keyway for straight line movement transversely of the periphery of the grinding wheel 6. This sleeve may be manually moved lengthwise of the shaft 58 and transversely of the periphery of the grinding wheel by any convenient means. As shown, it is formed with a laterally extending ear 64 to which is pivoted the bifurcated end of a link 66, the outer end of which is connected to one end of a bell crank 68, pivotally mounted upon a post upstanding from a lateral offset 55 at

the lower edge of the frame 54. The outer end of the bell crank lever constitutes an operating handle, (Fig. 3) by means of which the sleeve may be reciprocated upon the guiding rod 58.

The sleeve 62 is provided adjacent to its opposite ends with upstanding threaded bosses 72 into which are threaded the lower ends of vertically extending guide rods 74 on which are guided for vertical movement complementary sleeves 76 having a connecting web 78 terminating at its lower end below the sleeves in an arm 80 laterally offset (Fig. 1) and provided with a roller 82 and normally resting by gravity upon the edge 80 of a templet 84 removably fixed, as by set screws, in an appropriate channel formed in the upper edge of a bar 86 outwardly offset from the frame 54. The connected sleeves 76 form part of a support for the knife holder, as will be seen later.

At its upper end the web 78 connecting the sleeves 76 terminates in a sleeve 88 extending in substantial alinement with the periphery of the grinding wheel 6 and at right angles to the complementary sleeves 76. Preferably the sleeve 88 is formed integrally with the sleeves 76 and the web 78.

This sleeve 88 supports for movement toward and from the periphery of the grinding wheel 6 the spindle 90 of a knife holder, the rearward or inner end of the spindle being provided with an integral laterally curved bar 92 the opposite ends of which are provided with alined plates 94, having their adjacent faces channeled as at 96 (Fig. 3), to form seats for the edges of a knife, such as the heel broasting knife 98, best seen in Fig. 1. The offsets 94 are provided with horizontally extended threaded bores and knife clamping blocks 100, correspondingly bored, are brought into clamping engagement with the faces of the knife at its opposite sides between its cutting and its rear edges by means of clamping screws 102 having their outer ends provided for convenience with operating handles 104.

The side bars of the frame 54 are forwardly curved in the direction of the grinding wheel 6, and centrally of the top bar of the frame and in alinement with the periphery of the grinding wheel is a threaded sleeve 106 preferably formed integrally with the frame. This sleeve serves to carry a guiding pin 108 threaded through the sleeve 106 and having a check nut 110 to lock it in adjusted position. This guide pin will be adjusted so that its forward end will engage the rear face of a knife clamped between the plates 96, 100 during relative movement of the knife transversely of the periphery of the grinding wheel to maintain successive grinder-contacting portions of the opposite knife face uniformly spaced from the end of the grinding pin so that a uniform beveled

edge may be secured by the grinding operation. The rear face of the knife will be maintained in guided engagement with the end of the pin 108 at all times by means of a 5 tension spring 112 having one end anchored to a stud projecting from sleeve 88 and having its other and rearward end secured to a stud depending from the spindle 90. Preferably, and in order to prevent any flexure 10 or yielding of the knife when under grinding pressure, bracing pins 114 are seated in vertical sockets in the clamping plates 94 closely adjacent to the knife seat and extend upwardly beyond the holder parallel with 15 and in contact with the rear face of the projecting portion of the knife adjacent to its side edges.

In operating the grinding mechanism, it 20 will be understood that the initial inclination at which the edge of the knife is held relatively to the periphery of the grinding member is determined by adjustment of the set screws 46, 48. The cutting edge of the knife is positioned closely adjacent to and 25 somewhat above the guiding pin 108 and is clamped in its position. The knife with its supporting frame, which has been initially moved away from the grinder for the insertion of the knife, is now moved inwardly, 30 through hand wheel 26, as previously described, to position the knife with its edge engaging the periphery of the grinding wheel 6 at the bevel predetermined by adjustment of the set screws 46, 48, as de- 35 scribed.

With a knife mounted in the knife holder and positioned relatively to the peripheral grinding edge of the wheel 6, as described, 40 the operation of the grinding machine will be as follows: The workman actuates the hand lever 68, reciprocating the carrier sleeve transversely of the periphery of the grinding wheel so that the full width of 45 the grinding edge of the knife traverses the grinding wheel.

Assuming that the supported knife is 50 transversely concaved as shown, and that its cutting edge is also concave, the action will be as follows: Transverse movement of the sleeve 62 will move the knife transversely of the edge of the grinding wheel, the projection of the knife being coincidently varied by the raising and lowering of sleeve 88 supporting the knife holder through the 55 action of the templet 84 upon the roll 82. As the knife traverses the periphery of the grinding wheel, the spring 112 will hold successive portions of the rear face of the knife pressed against the relatively stationary guiding pin 108, the spindle 90 sliding toward and from the periphery of the grinding wheel as the transverse curvature of the transversely moving knife approaches or recedes from the grinding wheel periphery. 60

Manifestly, in order to permit this auto-

matic determination of the line of traverse or transverse knife movement and the lateral turning movement of the knife the grinding wheel will be relatively narrow.

When transversely straight or flat breast- 70 ing knives are to be ground, (the edge of the knife, of course, being curved to conform to the shank of the shoe), the same parts are used without change, the coiled spring 112 maintaining successive portions of the rear 75 face of the transversely moving knife against the rounded end of the guiding pin so that the transverse path of movement of the straight knife is in a straight line while the appropriate templet 84 will cause the 80 projection of the knife to be varied during its traverse of the grinding wheel periphery so as to conform with the lengthwise curvature of the cutting edge of the knife, as previously described. The described construction is therefore employed with equal 85 facility for both transversely straight and curved knives without any special adjustment or change being necessary, the guiding means provided being arranged to coöperate 90 with the knife automatically to conform the line of transverse movement to the transverse contour of the guided knife while the templet automatically and coincidently varies the projection of the edge of the 95 knife being ground. The immediate knife holding part 90, in addition to having transverse movement with the carriage 62, is supported for and capable of independent movement in a direction having components sub- 100 stantially perpendicular to the line of transverse movement and horizontally toward or from the periphery of the grinding wheel. The specific direction and relative value of the components, is variable, depending upon 105 and determined by the knife edge curvature and the transverse knife contour.

Having thus described my invention, what I claim as new and desire to secure by Letters Patent of the United States is: 110

1. A machine of the class described, having in combination, a grinding member and knife holding means constructed and arranged for relative traverse to grind the edge of a knife, and traverse guiding means constructed and arranged to direct said relative traversing movement along a line automatically determined by the coöperation of said guiding means with the transverse face of a knife mounted in said holding means. 115

2. A machine of the class described having, in combination, a grinding member and a knife holding means supported for relative movement transversely of the grinding member, and guiding means arranged to co-operate with the knife during such relative movement to conform the line of traverse to the transverse contour of the knife. 125

3. A machine of the class described hav- 130

1. A machine of the class described having, in combination, a grinding member and knife holding means constructed and arranged for movement along a straight line transversely of the grinding member, and guiding means arranged to coöperate with the supported knife during said transverse movement of the knife to maintain successive portions of the edge of the transversely moving knife uniformly in contact with the surface of the grinding member.
2. A machine of the class described having, in combination, a grinding member and knife holding means supported for relative movement transversely of the grinding member and including a knife holder mounted for independent movement toward and from the grinding member, and guiding means arranged to coöperate with the supported knife during such transverse movement automatically to position the knife holder relatively to the grinding member to conform the line of transverse knife movement to the transverse contour of the guided knife.
3. A machine for grinding transversely curved knives having, in combination, a grinding wheel of relatively narrow peripheral grinding surface, knife holding means constructed and arranged for movement transversely of the periphery of the grinding wheel and for coincident movement toward and from said periphery, and guiding means arranged to coöperate with one face of the transversely moving knife to move said knife holding means toward or from the wheel periphery to maintain successive portions of the transversely curved edge of the knife uniformly in contact with the periphery of the grinding wheel.
4. A machine of the class described having, in combination, a grinding member and knife holding means constructed and arranged for relative traverse, with a guiding member determinately positioned to engage the rear face of the knife during such relative traverse to maintain successive grinder-contacting portions of the opposite knife face uniformly spaced from said guiding member.
5. A machine of the class described having, in combination, a grinding member and a carriage arranged for relative traverse, a knife holder moving with said carriage and mounted for independent movement toward and from said grinding member, a guiding member determinately and fixedly positioned to engage the rear face of the knife during such relative traverse to maintain successive grinder-contacting portions of the opposite knife face uniformly spaced from said guiding member.
6. A machine of the class described having, in combination, a grinding member and knife holding means supported for relative movement transversely of the operative face of the grinding member, and guiding means constructed and arranged to coöperate with the knife during such relative transverse movement to effect relative traverse along a line automatically determined by the transverse contour of the knife and including a templet coöperating with the knife holding means automatically to effect bodily longitudinal projecting movement of the knife in the path of and during such traversing movement.
7. A machine of the class described having, in combination, a grinding member and a carriage arranged for relative traverse, a knife holder moving with said carriage and mounted for independent movement toward and from said grinding member, a guiding member determinately and fixedly positioned to engage the rear face of the knife during such relative traverse to maintain successive grinder-contacting portions of the opposite knife face uniformly spaced from said guiding member, and means coöperating with said knife holder to maintain the rear face of the knife in contact with said guiding member during such relative traverse.
8. A machine of the class described having, in combination, a grinding wheel of relatively narrow periphery, a carriage arranged for movement in a straight line transversely of said wheel periphery, a knife holder moving with said carriage and mounted for independent movement toward and from said wheel periphery, and a guiding member determinately and fixedly positioned to engage the rear face of the knife as it is moved transversely to maintain successive grinder-contacting portions of the opposite knife face uniformly spaced from said guiding member whereby a uniformly ground knife edge is secured.
9. A machine of the class described having, in combination, a grinding member and knife holding means supported for relative movement transversely of the operative face of the grinding member, and guiding means arranged to coöperate with the knife during such relative transverse movement to effect relative traverse along a line automatically determined by the transverse contour of the knife, and coincidently to effect bodily longitudinal projecting movement of the knife in the path of and during such traversing movement.
10. A machine of the class described having in combination, a grinding member and knife holding means supported for relative movement transversely of the operative face of the grinding member, and guiding means constructed and arranged to coöperate with the knife during such relative transverse movement to effect relative traverse along a line automatically determined by the transverse contour of the knife and including a templet coöperating with the knife holding means automatically to effect bodily longitudinal projecting movement of the knife in the path of and during such relative traversing movement to vary the projection of the knife edge to conform with the longitudinal curvature of said edge.
11. A machine for grinding breasting knives having, in combination, a grinding wheel having a relatively narrow peripheral grinding surface, knife holding means supported for movement transversely of the periphery of the grinding wheel and toward and from said periphery, knife guiding means constructed and arranged to coöperate with and position the knife holding means during such transverse movement to effect traverse of the knife along a line corresponding to and automatically determined and controlled by the transverse contour of the knife, and additional knife guiding means comprising a templet having a guiding edge complementary to the curve of the knife edge lengthwise of the edge and arranged to coöperate with the knife holding means during its transverse movement to effect variable bodily longitudinal projec-

tion of the knife conforming to said lengthwise curvature of the edge uniformly to bevel said edge in grinding.

12. A machine of the class described, having, in combination, a grinding wheel, a relatively rigid frame, a carriage guided on said frame for sliding movement transversely of the periphery of the grinding wheel, and knife holding means mounted on and moving with said carriage transversely of the grinding wheel and independently and coincidentally movable substantially perpendicularly to the line of transverse movement and also coincidentally movable toward and from the periphery of the grinding wheel.

13. A machine of the class described having, in combination, a grinding wheel, a relatively rigid frame, a carriage mounted on said frame for sliding movement along a line substantially parallel to the axis of said wheel and transversely of its periphery, knife holding means mounted on and moving with said carriage and independently and coincidentally movable substantially perpendicularly to the line of transverse carriage movement, with guiding means co-operating with the knife holding means automatically and determinately to control said perpendicular movement of the knife.

14. A machine of the class described having, in combination, a grinding wheel, a relatively rigid frame, a carriage mounted on said frame for straight line movement substantially parallel to the axis of the grinding wheel, knife holding means mounted on said carriage for straight line movement therewith and for coincident and independent movements substantially perpendicularly of the line of carriage movement and substantially horizontally toward and from the periphery of the grinding wheel, guiding means co-operating with the held knife and with the knife holding means automatically to position said holding means during straight line carriage movement to effect transverse knife movement in a line corresponding to and determined by the transverse contour of the knife, and means to vary the perpendicular position of the knife holding means to cause the beveled edge of the transversely moving knife to be presented to the grinding wheel periphery along a line conforming to the lengthwise curvature of the knife edge.

15. A machine of the class described having, in combination, a grinding wheel, a relatively rigid frame, a carriage mounted on said frame for sliding movement transversely of the periphery of said wheel, knife holding means mounted on and movable transversely with said carriage and independently movable toward and from the periphery of said grinding wheel, guiding means determinately and fixedly positioned

relatively to said carriage, knife holding means and grinding wheel and arranged to engage the rear face of a transversely moving knife to maintain successive portions of said rear face uniformly spaced from the periphery of the grinding wheel, and means operative to hold the rear face of the knife in contact with said guiding means during traverse of the knife.

16. A machine of the class described having, in combination, a grinding wheel, a relatively rigid frame, a carriage mounted on said frame for sliding movement along a straight line transversely of the periphery of said wheel and substantially parallel with its axis, and a knife holder mounted on and moving transversely with said carriage and supported on said carriage for independent movements in directions substantially perpendicular to the line of transverse movement and transversely of said line of movement toward or from the grinding wheel periphery.

17. A machine of the class described having, in combination, a grinding wheel, a relatively rigid frame, a carriage mounted on said frame for sliding movement transversely of the grinding wheel periphery, and a knife holder mounted on said carriage and moving transversely with said carriage and supported for independent movement in a direction having components substantially perpendicular to the line of transverse movement and horizontally toward or from the grinding wheel periphery, with guiding means co-operating with said knife holder arranged automatically to effect such independent movement of the knife holder coincidently with transverse movement of the carriage and knife holder and in determinate relation to the lengthwise edge curve and transverse contour of the supported knife.

18. A machine of the class described having, in combination, a grinding wheel, a relatively rigid frame, a carriage guided on said frame for straight line movement transversely of the periphery of the grinding wheel, a knife-holder support mounted on said carriage for transverse movement with the carriage and for independent vertical movement substantially perpendicularly to the line of transverse movement, and a knife holder mounted in said support for transverse and vertical movement therewith and for independent movement toward and from the periphery of the grinding wheel.

19. A machine of the class described having, in combination, a grinding wheel, a relatively rigid frame, a carriage guided on said frame for straight line movement transversely of the grinding wheel periphery, a knife holder support mounted on said carriage for transverse movement with the carriage and for independent vertical movement substantially perpendicular to the line

of transverse movement, a templet arranged to coöperate with said support during transverse carriage movement determinately to effect independent vertical movement of said

support, a knife holder mounted on said support for transverse and vertical movement therewith and for independent sliding movement toward and from the grinding wheel periphery, a guide determinately positioned on said rigid frame to engage the rear face of a knife carried by and moving with said carriage and support to maintain successive portions of the cutting edge of said knife in contact with the periphery of the grinding wheel, and means to maintain said face of the knife against said guide.

22. In a machine of the class described, in combination, a supporting bracket having a longitudinally slotted arm, a bar supported by and guided in said slotted arm for adjustment longitudinally of the arm, a threaded adjusting spindle, a connection between said spindle and bar longitudinally movable by rotation of the spindle to effect lengthwise adjusting movement of said bar, and a knife-carrying frame supported by and adjustable with said bar.

23. In a machine of the class described, a knife holder having means to engage and clamp opposite portions of the side edges of a knife between its cutting and rear ends, and backing means arranged to engage the clamped knife beyond said holder to brace the projecting portion of the knife against distortion or flexure by grinding pressure.

24. In a machine of the class described, in combination, a support, a knife holder slidably mounted thereon and having means to clamp a knife, a rigidly supported guide pin to engage a face of a clamped knife, and a spring connecting said support and knife holder and operative to maintain the face of a clamped knife in contact with said guide pin.

In testimony whereof I have signed my name to this specification.

ALFRED B. FOWLER.
